AIR-CAUSTIC SWEETENING

Mathew L. Kalinowski, Chicago, and Garbis H. Meguerian, Park Forest, Ill., assignors to Standard Oil Company, Chicago, Ill., a corporation of Indiana

No Drawing. Application April 16, 1954,
Serial No. 423,834

3 Claims. (Cl. 196—29)

This invention relates to the sweetening of cracked naphtha. More particularly, the invention relates to the sweetening of cracked naphthas by a process involving aqueous caustic treating agent, catalyst, free oxygen and free sulfur.

It is common to sweeten virgin naphthas by a process involving contacting said naphtha with an aqueous caustic solution containing a mercaptan oxidation promoter and free oxygen. For thermally cracked naphthas and most catalytically cracked naphthas, such a process is relatively ineffective. In the case of these refractory sour cracked naphthas, the above process has been modified by carrying out the contacting in the presence of free sulfur. While this process is effective to sweeten cracked naphthas having a mercaptan number of not more than 20, the use of free sulfur results in an undesirable lowering of the octane number of the sweet naphtha as compared with the octane number of the sour naphtha. An object of the invention is a sweetening process wherein the loss of octane number owing to the use of free sulfur is decreased. Other objects will become apparent in the course of the detailed description. The process of the invention involves sweetening sour cracked naphthas having mercaptan numbers of not more than 20, wherein the naphtha is contacted with an aqueous alkaline treating agent which contains a catalytic amount of alkyl phenols in the presence of free oxygen and free sulfur, in an amount sufficient to sweeten said naphtha; said contacting is carried out at a temperature of at least about 80° F. for a time sufficient to produce a product naphtha that is sweet to the doctor test; said contacting is further carried out in the presence of an effective amount of an aliphatic amine which is essentially insoluble in water, which amine has been introduced into the sour naphtha prior to the addition of free sulfur to said sour naphtha.

The aliphatic amines utilized in the process of this invention are the oil soluble amines which are also essentially insoluble in water, or more particularly, in aqueous caustic solutions. These aliphatic amines include (a) primary aliphatic amines containing at least 8 carbon atoms, for example, octylamine, decylamine, laurylamine, cetylamine, sterylamine; (b) secondary aliphatic amines containing at least 5 carbon atoms in each aliphatic group, for example, di-n-amylamine, di-isoamylamine, and di-octylamine; (c) tertiary aliphatic amines containing at least 3 carbon atoms in each aliphatic group, for example, tri-n-propylamine, tri-isopropylamine, tri-n-butylamine, tri-isobutylamine, tri-n-amylamine, tri-isoamylamine, and tri-octylamine. The tertiary aliphatic amines do not react with free sulfur to form hydrogen sulfide. Since free sulfur is present in the sweet oil in virtually all these sweetening operations, the tertiary aliphatic amines are the preferred amines. The tri-n-butylamines are preferred for reasons of cost.

At least an amount of the aliphatic amine must be present in the oil to improve the quality of said oil. In general, at least about 0.001 weight percent, based on oil, of the aliphatic amine should be present. Amounts up to about 10 weight percent may be utilized. These large amounts are particularly suitable when extremely refractory oils are being treated; and when the aliphatic amine

2

is recovered from the sweet oil by treating the oil with an acid that is reactive with the amine to form an oil insoluble salt. This salt may be decomposed by treatment with aqueous caustic solutions to recover the aliphatic amine for reuse in the process. In general, it is preferred to operate with between about 0.01 and 0.1 weight percent of aliphatic amine.

The aliphatic amine may be added to the sour oil prior to the addition of aqueous agent, or the aliphatic amine may be added to the mixture of sour oil and aqueous agent. In any case, the aliphatic amine must be present in the sour oil prior to contacting the sour oil with free sulfur. It is preferred to add the aliphatic amine to the sour oil prior to commencing the sweetening operation.

The feed naphtha to the process of this invention is a cracked naphtha and preferably a naphtha having an ASTM end point of not more than 425° F. The cracked naphtha may be a thermally cracked naphtha derived from refinery operations such as vis breaking, coking, gas oil cracking, heavy naphtha reforming, etc. Or, the cracked naphtha may be a catalytically cracked naphtha from refinery operations such as fluid catalytic cracking, moving bed catalytic cracking, cracking in the presence of hydrogen, etc.

The sour naphtha feed may be prewashed with a weak aqueous caustic solution to remove H₂S, but it is not essential that the feed be H₂S free. A cracked naphtha which has been subjected to a conventional caustic-solvent extraction process to remove a portion of the mercaptans is a satisfactory feed to the process.

Cracked naphthas having a mercaptan number in excess of about 20 are not readily sweetened by this process and it is preferred to operate with a sour naphtha having a mercaptan number of not more than 20.

The aqueous treating agent used in this process is present in an amount at least sufficient to form a separate phase. Sweetening can be obtained with amounts of agent just great enough to impart a haze to the naphtha. For most operations the amount of the aqueous treating agent will be about 10 to about 200 volume percent based on the feed naphtha. It is preferred to use about 25% to about 50% by volume of aqueous treating agent in this process.

The caustic component of the aqueous treating agent may be sodium hydroxide, potassium hydroxide, or mixtures thereof. The caustic is present in the treating agent in the form of free-alkali and in chemical combination with the alkylphenols. Furthermore, some of the caustic may be combined with acidic contaminants in the treating agent. Free caustic must be present, preferably, at least about 5 weight percent. Higher concentrations of caustic may be used and in some cases a saturated solution may be desirable, e. g., about 50% of NaOH. It is preferred that the total caustic content, i. e., free and combined caustic, of the aqueous treating agent be between about 15 and 25 weight percent.

The alkylphenols used in this invention may be any alkylhydroxy-benzene, such as cresol, xylenol, etc. The preferred alkylphenols are those naturally occurring in petroleum hydrocarbons, particularly in hydrocarbons derived from thermal cracking and catalytic cracking processes. These alkylphenols may be obtained by contacting the petroleum hydrocarbon with concentrated aqueous caustic solution. The cresols derived from cracked naphtha have an ASTM boiling range from about 370° F. to about 440° F. Alkylphenols occur in petroleum hydrocarbons boiling in the heavier-than-gasoline range, i. e., hydrocarbons boiling from about 350° F. to about 600° F. These alkylphenols are usually called "heavy xylenols" and may be obtained by contacting cracked gas oils and many virgin gas oils with concentrated aqueous caustic solution such as a 40% solution. These heavy xylenols

70

have an ASTM boiling range between about 375° F. and 560° F. or higher.

The alkylphenols present in the aqueous treating agent act as solutizers for the mercaptans. The alkylphenols also aid in preventing the presence of corrosive sulfur in the naphtha, and it is possible that they do this by reacting with the excess free sulfur. It is necessary to have at least a catalytic amount of alkylphenols present in the aqueous treating agent, and preferably at least about 2 volume percent. It is advantageous to have more alkylphenols present and in some cases a saturated solution may be desirable. However, these alkylphenols increase the viscosity of the agent and may produce phase separation difficulties. It may be desirable to limit the alkylphenols to about 30 volume percent when using sodium hydroxide, preferably about 20; somewhat higher amounts may be used when using potassium hydroxide. It is preferred to use between about 5 and 20 volume percent alkylphenols in the aqueous treating agent.

The free oxygen may be introduced into the process either in the form of substantially pure oxygen, i. e., cylinder oxygen, or in the form of a free-oxygen-containing gas, e. g., air. Very slight amounts of free oxygen are needed to oxidize the mercaptans in the naphtha to disulfides, but at least an amount sufficient to oxidize the easily oxidizable mercaptans is desirable since the sulfur is particularly required for the oxidation of mercaptans which are difficult to oxidize. The amount of free oxygen required will increase with increasing mercaptan number of the sour naphtha. Usually 5 s. c. f. of air will be sufficient for the production of a sweet product. It is preferred to add between about 0.2 and 2 standard cubic feet of free oxygen per barrel of sour naphtha. When air is used, from about 1 to about 10 s. c. f. of air are added per barrel of sour naphtha.

The amount of free sulfur must be at least an effective amount but less than the amount which gives a corrosive product naphtha. The use of free sulfur effects favorably the contacting temperature and contacting time. The amount of free sulfur required increases with increasing mercaptan number of the naphtha feed. The use of more than about 1.8 pounds of sulfur per 1000 barrels of naphtha feed per mercaptan number of the feed appears to have an adverse effect on the TEL susceptibility of the product naphtha, and a corrosive naphtha product may result. Amounts of free sulfur as low as 0.5 lb./1000 bbls./mercaptan number or lower may be sufficient with some naphthas. Preferably, between about 0.9 to about 1.6 pounds of sulfur per 1000 barrels of naphtha feed per mercaptan number of said feed is used to obtain a doctor sweet product with thermally cracked naphthas having a boiling range between about 120° F. and 400° F. When the particular type of mercaptans present in the naphtha are very difficult to oxidize, the amount of sulfur required to obtain a sweet naphtha product will correspond more closely to the 1.6 figure than to the 0.9 figure; this is the case normally with naphthas having ASTM end points appreciably above 400° F.

Normally, the practical extremes of temperature in which sweetening will be carried out are from about 80° F. to 210° F. Temperatures below about 100° F. are preferred for use on naphthas having substantial quantities of light ends, i. e., butanes and pentanes, to avoid substantial losses of these by evaporation during the processing. It is desirable to use higher temperatures as the sweetening reaction is accelerated by higher temperatures. Therefore, for naphtha feeds boiling between about 120° F. and 400° F., temperatures of about 120° F. to about 160° F. are preferred. For naphthas which are more refractory, i. e., harder to sweeten, temperatures above 160° F. may be used.

The mixture of amine, free sulfur, agent, naphtha and free oxygen should be maintained intermingled for a

time sufficient to complete the sweetening reaction, i. e., to produce a naphtha having a mercaptan number substantially less than 1. The required contacting time is dependent on the mercaptan number and the type of naphtha, but normally this time will be between about 1 minute and 60 minutes. For most feeds, a contact time of from about 2 to about 20 minutes will be sufficient.

After the completion of the sweetening reaction, the mixture of treating agent and naphtha is settled for a time sufficient to separate the product naphtha from the lower aqueous phase. The aqueous phase is usually suitable for recycle to the initial contacting step. However, in the course of time there is a buildup of thiosulfates and other by-product salts which interfere with the sweetening process and reduce the free caustic concentration. The cresols also build up in the treating agent, when the naphtha feed has not been prewashed with caustic to remove H₂S or extracted with caustic-cresylate solution for mercaptan number reduction. It is therefore desirable to periodically discard the treating solution and use fresh solution; or to continuously withdraw a portion of the treating agent and replace it with fresh solution.

The results obtainable by the process of this invention are illustrated by the working example set out below. It is to be understood that this example is illustrative only and does not limit the scope of usefulness of the process.

Example

The feed to the tests was a cracked heavy naphtha derived from the thermal cracking of a virgin gas oil. This naphtha boiled between 200° and 390° F. and had a mercaptan number of 27.6 (mg. of mercaptan sulfur per 100 ml. of naphtha).

Test 1.—A 500 ml. sample of the sour naphtha was placed into a three-necked flask. To the flask was added 125 ml. of aqueous caustic-cresylate solution which contained about 10 weight percent of free NaOH and a cresol concentration of about 20 volume percent. These cresols had been obtained by caustic extraction of sour cracked naphtha. In this test, 69 mg. of free sulfur were added to the contents of the flask. The mixture was heated to 90° F. and air was introduced into the flask for 15 minutes. The naphtha was decanted from the aqueous agent and then water washed to remove occluded agent. The product naphtha was sweet to the doctor test.

Test 2.—Another portion of the sour naphtha was sweetened as in Test 1, except that 0.005 weight percent of tri-n-butylamine was added to the sour naphtha before the aqueous agent was added to the flask.

Test 3.—Another portion of sour naphtha was sweetened according to the procedure of Test 1 and then 0.005 weight percent of tri-n-butylamine was added to the sweet oil.

Since very slight differences in octane number are involved, the octane number change by the various methods of treating was determined by a differential procedure, using the octane number of the sour feed naphtha as a reference point. Octane numbers were determined of the naphthas as is, i. e., clear and also containing 1 and 3 cc. respectively of commercial tetraethyllead solution.

The results of these tests are set out below:

Naphtha From—	Differential Octane Number, CFR-R		
	Clear	1.0 cc.	3.0 cc.
Feed (actual O. N.)	71.2	79.3	84.4
Test 1	-0.5	-0.5	-1.1
Test 2	+0.1	+0.1	+0.1
Test 3	0.0	-0.4	-1.0

The results of Tests 1 and 3 show that the butylamine has no beneficial effect on the leaded octane number of the sweet oil when added to the sweet oil. The results of Test 2 show that the adverse effect of sulfur on the octane number of the naphtha is completely overcome. By the use of the process of this invention, it is possible to gain between one-half and one octane number over the conventional process. This represents a significant economic saving in tetraethyl-lead usage to attain a given octane number.

Thus having described the invention, what is claimed is:

1. A sweetening process which comprises (1) adding to a sour cracked naphtha, having an ASTM endpoint of not more than 425° F., between about 0.001 and 10 weight percent of at least one aliphatic amine selected from the class consisting of (a) primary aliphatic amines containing at least 8 carbon atoms, (b) secondary aliphatic amines containing at least 5 carbon atoms in each aliphatic group, and (c) tertiary aliphatic amines containing at least 3 carbon atoms in each aliphatic group, (2) contacting said amine-containing sour naphtha with (i) an aqueous treating agent consisting essentially of water, caustic and alkylphenols, said agent containing at least about 5 weight percent of free caustic, at least about 2 volume percent of alkylphenols and no plumbite, said

5
10
15

agent being present in an amount between about 10 and 200 volume percent, based on said amine-containing sour naphtha, (ii) free oxygen in an amount between about 0.2 and 2 standard cubic feet per barrel of said amine-containing sour naphtha and (iii) free sulfur in an amount to render said amine-containing sour naphtha essentially sweet to the Doctor test, (3) maintaining the contents of said contacting zone of step 2 at a temperature between about 80° F. and about 200° F. for a time at least sufficient to convert essentially all the mercaptans in the sour naphtha and to produce an essentially sweet naphtha and (4) separating an essentially sweet amine-containing naphtha from aqueous agent.

2. The process of claim 1 wherein said amine is tri-n-butylamine.

3. The process of claim 1 wherein said amine is present in an amount between about 0.001 and 0.1 percent.
